CENTRIFUGAL PUMP

Filed Aug. 16, 1950

UNITED STATES PATENT OFFICE

2,672,821

CENTRIFUGAL PUMP

Horace M. Montgomery, Mansfield, Ohio, assignor
to Gorman-Rupp Industries, Inc., Bellville,
Ohio, a corporation of Ohio

Application August 16, 1950, Serial No. 179,786

8 Claims. (Cl. 103—103)

1

This invention relates generally to centrifugal pumps and particularly to a new pump which consists of but a few, simple parts, which is resistant to corrosion and abrasion and which is self-descaling and self-cleaning.

There has long existed a demand in certain industries, particularly the washing machine industry, for a small centrifugal pump which could be made inexpensively from a few, simple parts and which would be resistant to liquids passing through it and which would rid itself of solids depositing thereon out of such liquids. Although many efforts have been made to satisfy this demand, no one, so far as I know, has devised a pump which would meet this demand.

The present invention solves this long standing problem. An embodiment of this invention comprises a flexible impeller housing which can flex during the pumping action and another embodiment adds thereto a liner for the cooperating housing part and also serves as a gasket and additionally may serve as a shaft seal.

The present invention will be better understood by those skilled in the art from a consideration of the following description and the accompanying drawings, in which:

Fig. 1 is a side elevational view, partly in central section, of one form of pump embodying the present invention;

Fig. 2 is a partly sectional, perspective view of the diaphragm of the pump of Fig. 1;

Fig. 3 is a partly sectional, side, elevational view of a modified form of the main body part of a pump embodying the present invention; and

Fig. 4 is a central, sectional, fragmentary view of a modified form of pump.

In Fig. 1 the pump is shown as comprising a main housing or body 1, a housing closure 2, a diaphragm 3, a reinforcing ring 4, an impeller shaft 5 and an impeller 6.

The main housing part 1 is generally tubular and includes a cylindrical wall 10 from which a discharge tube 11 extends tangentially, and an intake end 12 provided with a central tube 13 through which liquid may enter the impeller chamber which is within the confines of cylindrical wall 10.

The end closure 2 comprises a disk 14 and a centrally disposed outwardly projecting tube 15 attached thereto through which the impeller shaft 5 extends, the impeller 6 being mounted on shaft 5 in the impeller chamber. Near its outer periphery disk 14 is formed with a right angled recess to receive the edge portion of diaphragm 3 and the open end of wall 10. As is better shown

2

in Fig. 2, the diaphragm 3 has a peripheral portion 20 extending at substantially right angles to flange 21, the latter being disposed at right angles and attached to the central part 22 of the diaphragm. The axial portion of diaphragm 3 includes a tubular part 23 projecting outwardly parallel to flange 21 and an end wall 24 provided with oppositely extending and tapering annular lips 25 to fit closely around the impeller shaft 5 for a purpose presently to be described.

The right angle portions 20 and 21 of the diaphragm 3 fit snugly in the right angled recess in the outer portion of disk 14 and the open end of main body 10 and the outwardly extending annular flange 30 thereof are suitably dimensioned to fit closely against diaphragm walls 20 and 21, as is better shown in Fig. 1. The ring 4 is preferably seated in an annular, shallow notch 31 in tubular wall 10 and is clamped against the flange 30 of part 1 and holds the flange 30, part 20 of diaphragm 3 and disk 14 in assembled relation when screws 32 or other suitable securing means are assembled therewith substantially as shown in Fig. 1.

The body 1 is preferably composed of rubber, or other elastomeric material which is resistant to corrosion and abrasion, and is sufficiently flexible, particularly in the tubular part 10 thereof, to flex under the impulses to which it is subjected during the pumping action. As the impeller rotates, the pressure applied to the part 10 increases when an impeller blade approaches the outlet 11 and decreases when the blade passes beyond the outlet. This action is observable as a pulsation which causes the body 10 to expand and contract to a certain extent. Due to this constant flexing, any solids which may deposit on the walls thereof from liquid standing in or passing therethrough will be dislodged so that this body 1 will be substantially self-descaling and self-cleaning.

The diaphragm 3 is preferably composed of thin rubber or rubber-like material which is resistant to corrosion and abrasion and which has a greater degree of resiliency and flexibility than the material of body 1. The sealing lips 25 which extend in opposite directions and surround and closely engage at their edges with the shaft 5 serve to seal the shaft against the flow of fluid along the shaft in either direction. Due to their flexibility, these lips maintain such sealing action even when the shaft is misaligned or rotates eccentrically. The diaphragm 3 also serves as a liner for housing part 2 since it protects that member from contact with the materials being

propelled through the pump. The diaphragm also serves as a gasket between members 1 and 2 and, due to the right angular configuration of its marginal portions 20 and 21 and the location of these parts between the correspondingly shaped and opposed portions of parts 1 and 2, the diaphragm tends to lie close against the surface of part 2 throughout its full extent. In other words, any tendency of the diaphragm to bulge and move away from contact with part 2 which might be induced by the clamping ring 4 is overcome by reason of the fact that the part of the gasket which is thereby placed under compression is removed from the plane of the diaphragm part which serves as a liner. Any spreading or deformation of the portion 23 of the diaphragm is confined to the angular recess on member 2 and is ineffective to cause distortion of part 22 of the diaphragm which is in contact with the liquid. Since the rubber of body part 1 is flexible and deformable, it may serve as a seal when clamped against the other body part 2 in the absence of the diaphragm.

Fig. 3 shows a modification of the main housing part 1 of Fig. 1, the modification residing mainly in the manner of uniting the clamping ring and the main housing part. In this figure, 40 designates the main housing with a tangential tubular outlet 41, an axial inlet tube 42 and an open end 43 to be closed, as by the part 2, and diaphragm 3 of Figs. 1 and 2. Instead of the loose or separate clamping ring 4 of Fig. 1, a ring 44 is shown as being embedded in member 40 near its open end. As will be understood, ring 44 is molded in place during the molding of part 1. Screws 32, or other suitable securing means, are used to hold parts 40 and 2 in assembled relation.

Fig. 4 shows a pump quite like that shown in Figs. 1 to 3 but differs therefrom primarily in the manner of supporting and sealing the shaft. In this device the main housing part 50 is quite like part 1 of Fig. 1. Housing part 51 differs from corresponding part 2 of Fig. 1 in having axially spaced, inwardly extending, annular flanges 52 and 53. The impeller 54 is carried by a shaft 55 which has a bearing in flange 53 and extends through a sleeve 56 which has a close fit in the central opening of flange 52. The end of sleeve 56 within the impeller chamber is notched to bear against the inner surface of diaphragm 57 and press it against the inner face of member 51, thereby to seal against ingress of liquid between the diaphragm and part 51. At its outer end sleeve 52 bears against a ring 58 which carries a packing ring 59 to bear against and seal shaft 55 against flow of liquid therealong in either direction. A spring 60 surrounding shaft 55 and bearing at one end against a shoulder thereof and against ring 58 at the other end tends to maintain the parts in assembled position. It will be noted that there is a small clearance between the shaft 51 and the sleeve 56 through which it passes. However, liquid may not pass through this space beyond ring 58 because of the sealing ring 59. In case of extreme "whip" or vibration of shaft 55, the sleeve 56 may also serve as a bearing to limit such extreme action.

Having thus described the present invention so that others skilled in the art may be able to understand and practice the same, I state that what I desire to secure by Letters Patent is defined in what is claimed.

What is claimed is:

1. A centrifugal pump comprising a two part body defining an impeller chamber, an impeller

in said chamber and a shaft attached to the impeller and extending out of said chamber, one of said body members being cup-shaped and having inlet and outlet openings, the walls of said body consisting of self-supporting elastomeric material capable of flexing inwardly and outwardly relative to their normal position under forces created during pumping action, and means securing said body parts in assembled position.

2. A centrifugal pump comprising a two part body defining an impeller chamber, an impeller in said chamber and a shaft attached to the impeller and extending out of said chamber, one of said body members being cup-shaped and having inlet and outlet openings, the walls of said body consisting of self-supporting elastomeric material capable of flexing inwardly and outwardly relative to their normal position under forces created during pumping action, said body member having an open end, a rigid member embedded in said member adjacent to said open end, and means securing the annulus and adjacent portions of said body parts and said rigid member together with fluid sealing pressure.

3. A centrifugal pump comprising a two part body defining an impeller chamber, an impeller in said chamber, one of said body members being cup-shaped and having inlet and outlet openings, the walls of said body consisting of self-supporting elastomeric material capable of flexing inwardly and outwardly relative to their normal position under forces created during pumping action, a diaphragm composed of resilient material and disposed at the open end of said cup-shaped member, the other body member being disk-shaped and bearing against the outer side of the diaphragm, means securing the members and diaphragm together at their peripheries with fluid sealing contact, a shaft extending through said disk-shaped member and diaphragm and connected to said impeller, and means about the shaft for sealing against flow of liquid lengthwise thereof.

4. A centrifugal pump comprising a two part body defining an impeller chamber, an impeller in said chamber, one of said body members being cup-shaped and having inlet and outlet openings, the walls of said body consisting of self-supporting elastomeric material capable of flexing inwardly and outwardly relative to their normal position under forces created during pumping action, a diaphragm composed of resilient material and disposed at the open end of said cup-shaped member, the other body member being disk-shaped and bearing against the outer side of the diaphragm, means securing the members and diaphragm together at their peripheries with fluid sealing contact, a shaft extending through said disk-shaped member and diaphragm and connected to said impeller, and means about the shaft for sealing against flow of liquid lengthwise thereof, said shaft sealing means including an integral flexible portion of said diaphragm surrounding and engaging the shaft.

5. A centrifugal pump comprising a two part body defining an impeller chamber, an impeller in said chamber, one of said body members being cup-shaped and having inlet and outlet openings, the walls of said body consisting of self-supporting elastomeric material capable of flexing inwardly and outwardly relative to their normal position under forces created during pumping action, a diaphragm composed of resilient material and disposed at the open end of said cup-shaped member, the other body member being

disk-shaped and bearing against the outer side of the diaphragm, means securing the members and diaphragm together at their peripheries with fluid sealing contact, a shaft extending through said disk-shaped member and diaphragm and connected to said impeller, and means about the shaft for sealing against flow of liquid lengthwise thereof, said shaft sealing means including a flexible portion of said diaphragm having oppositely extending conical shaft-engaging lips.

6. A centrifugal pump comprising a two part body defining an impeller chamber, an impeller in said chamber, one of said body members being cup-shaped and having inlet and outlet openings, the walls of said body consisting of self-supporting elastomeric material capable of flexing inwardly and outwardly relative to their normal position under forces created during pumping action, a diaphragm composed of resilient material and disposed at the open end of said cup-shaped member, the other body member being disk-shaped and bearing against the outer side of the diaphragm, means securing the members and diaphragm together at their peripheries with fluid sealing contact, a shaft extending through said disk-shaped member and diaphragm and connected to said impeller, and means about the shaft for sealing against flow of liquid lengthwise thereof, said shaft sealing means including a shaft-receiving sleeve extending through said diaphragm and fitting closely in said other body member, and fluid-sealing means around the shaft in said sleeve.

7. A centrifugal pump comprising a two part body defining an impeller chamber, an impeller in said chamber, one of said body members having an end wall provided with a central inlet, an annular side wall provided with an outlet and an open end opposed to said end wall, said walls consisting of self-supporting elastomeric

30

40

material capable of flexing inwardly and outwardly relative to their normal position under forces created during pumping action, the other body member being disk-shaped and disposed in the open end of the first said member, and a shaft extending through said disk-shaped member and being connected to said impeller.

8. A centrifugal pump comprising a two part body defining an impeller chamber, an impeller in said chamber, one of said members being cup-shaped and having end and side walls composed of self-supporting elastomeric material capable of flexing inwardly and outwardly relative to their normal position under pumping forces, the other of said members being disk-shaped, disposed at the open end of said cup-shaped member, and having an axial recess, a diaphragm secured at its periphery between said members and having an axial portion disposed in and supported by the walls of said recess, said axial portion having oppositely extending, integral, conical parts terminating in annular free ends, and a shaft connected to said impeller, extending through conical parts and being sealed by said free ends against flow of liquid along said shaft.

HORACE M. MONTGOMERY.
